WILLIAM G. KENDALL, OF NEWARK, NEW JERSEY

HOLDING RING FOR COMPACT PLATES

Application filed March 8, 1928. Serial No. 260,083.

This invention relates to holding means for compact plates, and has for an object to provide an improved construction wherein the ring must be deformed in order to be placed in position, or cut so as to be contracted.

Another object of the invention is to provide a compact plate holding ring, wherein one or more corrugations are provided, whereby different shaped compact plates may be properly engaged and held resiliently and removably in place.

In the accompanying drawing—

Figure 1 is a longitudinal vertical sectional view through a vanity case with the lid shown open, and with an embodiment of the invention applied thereto.

Figure 2 is a view similar to Figure 1 but with the lid closed, and another form of holding ring arranged in the case.

Figure 3 is a view similar to Figure 2, but showing a different form of compact plate.

Figure 4 is a top plan view of the body of the case shown in Figure 1, together with the holding ring in an operative position but with certain parts distorted for permitting application and removal of the ring.

Figure 5 is a view similar to Figure 4 but showing the ring with the distorted parts pressed back into position.

Figure 6 is a perspective view of a modified form of ring to that shown in Figures 1 to 5 inclusive.

Referring to the accompanying drawing by numerals, 1 indicates the body of a vanity case, and 2 a lid hingedly connected thereto in any desired manner. The body 1 may be of any desired shape, but in the drawing, for the purpose of illustration, is shown round and is shown offset at 3 for presenting an annular shoulder 4. This shoulder is, of course, not very deep, and the thickness of the metal is not great, as it is preferably very thin sheet metal capable of being stamped and properly shaped as desired. As shown in Figure 1, there is provided a compact plate 5 of a well known design, and in order to hold this plate in position so as not to shift about or drop out, a holding ring 6 is provided, said ring having one or more pressed out portions 7 which present lips or

small resilient knobs engaging some part of the plate 5. The ring 6 is a sheet metal band and is provided preferably with a cut down or cut away portion at 8 whereby a comparatively narrow neck 9 is produced, which neck 55 is bent as shown in Figure 4 for constricting or reducing the diameter of the ring 6 and thereby permitting the ring to be applied or removed. After the ring has been applied as shown in Figure 4, the bent out portions 60 10 and 11 are pressed radially outwardly so as to restore the circular formation of the ring and then the parts will be as shown in Figure 5, with all or part of the ring 6 being positioned beneath the shoulder 4, whereby 65 the ring cannot be accidentally removed. In Figure 1, the ring is shown with a number of knobs or projections 7, while in Figure 2, the same ring is shown but it is provided with a number of corrugations 12. These 70 corrugations are preferably annular ring formations, but if desired, could be made in a spiral, though the separate ring formations are preferably as they present resilient shoulders beneath which part of the plate 5 may 75 extend, whereby the plate will be resiliently held in position.

In Figure 3, the same structure as shown in Figure 2 is present, except that the plate 5' is curved at its edges so that the upper 80 edge 13 of plate 5' will engage below the second bead or ridge 12. If a greater bend was produced in plate 5', it would engage the top bead. In this way beads are distributed over the entire surface of the ring 6' in order 85 to present compact plate engaging projections at desired points. The beads or projections 12 are spaced to receive the conventional and well known compact plates now in use, but if desired, these could be rearranged to accommodate any special plate desired, and the ring and beads caused to function in the usual manner.

Under some circumstances, it may not be desirable to provide for bending section 9, 95 and when this is the case, section 9 is divided as shown in the ring 5''. In this form of the invention, the cut away portion 8' is of the usual shape, while a line of division is provided at 14 and the ring 5'' formed to snugly 100 fit.

fit beneath the shoulder 4 when in normal position. By bringing the edges of the ring together at cut 14, the diameter is reduced and the ring may then be readily removed. If desired, ejecting means could be provided for ejecting the compact plates without disturbing the ring, or the plates could be merely removed by some implement, as for instance, a manicure scissors or nail file.

10 What I claim is:

1. A holding ring for compact plates, comprising an annular tubular ring structure formed with a plurality of pressed out portions for engaging and holding a compact plate in position, and a deformable restricted neck, said neck when deformed permitting the ring to be inserted and when forced back into its original position, acting to cause the ring to interlock with the vanity case in which it is positioned.

2. The combination with a vanity case having an annular shoulder, of a holding ring for compact plates adapted to be positioned in said case and beneath said shoulder, said ring being formed with compact plate holding means and with a deformable section acting to reduce the diameter of the holding ring when deformed and to restore the diameter when moved back to its original position whereby the holding ring may be inserted into said vanity case and then locked in position.

3. A holding ring for compact plates, comprising a continuous uninterrupted annular ring body formed with a plurality of pressed out portions for engaging in clamping position different kinds of compact plates and with a deformable section acting to reduce the diameter of the body when deformed and to restore the diameter of the body when moved back to its original position.

4. A holding ring for compact plates, comprising an undivided (continuous) annular tubular member formed with a plurality of spaced inwardly extending projections, and a deformable section acting to reduce the diameter of the tubular member when deformed and to restore the diameter of the tubular member when moved back to its original position, said deformable section being of less height than the remaining part of the tubular member.

5. A holding ring for compact plates, comprising a continuous and uninterrupted annular tubular ring body formed with a plurality of inwardly extending projections, said body being deformable at one point whereby the ring body may be expanded and contracted.

6. A holding ring for compact plates, comprising a continuous and uninterrupted tubular ring body formed with inwardly extending projections, said projections being spaced apart, and said body being reduced in

height at one point so that it may be deformed for enlarging or contracting.

Signed at New York in the county of New York and State of New York this 5th day of March, 1928.

WILLIAM G. KENDALL.
